UNITED STATES PATENT OFFICE

168,961

CHRISTMAS ORNAMENT

Biagio P. Melaragno, Johnston, R. I., assignor to Rosbro Plastics Corporation, a corporation of Rhode Island

Application June 20, 1952, Serial No. 20,284

Term of patent 7 years

(Cl. D29—1)

To all whom it may concern:

Be it known that I, Biagio P. Melaragno, a citizen of the United States of America, residing in Johnston, county of Providence, State of Rhode Island, have invented a new, original, and ornamental Design for a Christmas Ornament, of which the following is a specification, reference being had to the accompanying drawing, forming a part thereof:

Fig. 1 is a front elevational view of a Christmas ornament, showing my new design; and

Fig. 2 is a side elevational view thereof.

I claim:

The ornamental design for a Christmas ornament, substantially as shown.

BIAGIO P. MELARAGNO.
